UNITED STATES PATENT OFFICE.

EDGAR MALCOLM LEWIS, OF MOUNDSVILLE, WEST VIRGINIA.

DISPLAY BOX AND TRAY.

939,721.

Specification of Letters Patent.

Patented Nov. 9, 1909.

Application filed April 29, 1909. Serial No. 492,820.

To all whom it may concern:

Be it known that I, EDGAR M. LEWIS, a citizen of the United States, and a resident of Moundsville, in the county of Marshall 5 and State of West Virginia, have made certain new and useful Improvements in Display Boxes and Trays, of which the following is a specification.

My invention is an improvement in display boxes, and consists in certain novel constructions and combinations of parts hereinafter described and claimed.

The object of the invention is to provide a low priced, convenient, and compact combination of box and display tray for use in packing goods, which are intended to be displayed by the retailer, in the original boxes as received from the manufacturer.

A further object is to provide a device of 20 such simplicity that it cannot get out of order, inexpensive enough to be applied to the cheapest box and at the same time so complete that it may be used with the most elaborate and costly creation of the box makers' skill.

Referring to the drawings forming a part hereof—Figure 1 is a perspective view of the box with the tray removed; Fig. 2 is a similar view with the tray in place, of a box having a sliding cover; Fig. 3 is a longitudinal section of a box having a modified form of supporting device for the tray and the ordinary form of cover; Fig. 4 is a perspective view of the box shown in Fig. 3 with the cover removed and the tray elevated; and Fig. 5 is a similar view of a tray provided with another modified form of securing device.

The present embodiment of the invention 40 comprises a box 1, which may be of any desired construction, and supplied with a sliding lid 2 as shown in Fig. 2, or with the usual form of cover 3, shown in Fig. 3.

The tray consists of a bottom 4 having 45 ends 5 and sides 6, which are connected at their corners as at 7 in any suitable manner, and at one end the tray is provided with an angular clip 8 fitting against the end and the bottom thereof, the said clip being 50 provided at each end with an overhanging flange 9, 10, the flange 10 passing through the bottom of the box and overlying the upper face thereof as shown in Fig. 1.

At approximately the center of the bottom 55 of the tray the ends of a plurality of straps 11 are secured as at 12 and the other

ends of the straps are secured to the end of the box remote from the clip as at 13. The straps 11 are flexible, and may be made of any suitable material and are of such length that when the tray is inserted in the box, the straps will form a support for the end remote from the clip, the other end being supported by the engagement of the overhanging flange 9 with the end of the box.

In the form shown in Fig. 2, the straps are replaced by a cord which is doubled to form a loop, one of whose ends is engaged with the box as at 15, extending through openings 16 in the end thereof, the other end 17 extending through openings 14 in the bottom of the tray as shown in Fig. 2. The ends 15 and 17 prevent withdrawal of the cord, and the cord is of sufficient length to 75 form a support for the end of the box remote from the clip in the same manner as the straps.

In the construction shown in Fig. 3, a clip supports one end of the box, and a cord 80 18 is passed through spaced openings 19 at approximately the center of the tray, over the end of the box remote from the clip, and through spaced openings 20 in the end of the box, the ends of the cord being connected as at 21. The clip shown in Figs. 3 and 4 is a wire, doubled upon itself to form an open loop whose body portion is bent over to form an overlying lug 22 for engaging the end of the box, and the ends of the loop are passed through the bottom of the tray 90 and bent over on to the surface thereof as at 23. In this construction the cord answers the same purpose as the straps shown in Fig. 1, and the cord shown in Fig. 2.

In Fig. 5, the clip 8 is made use of, and also the straps 11 as shown in Fig. 1, but the ends of the straps instead of being secured to the end of the box are provided with clips 24, each of which is provided 100 with an overhanging flange 25 for engaging the end of the box.

In the use of the device, the tray may be packed with a display or sample layer of goods, and may be supplied with fancy paper trimming, pictures, advertising matter, or price card. When a sale is made, the tray is elevated out of the box and moved to one side thereof and the goods sold are taken from the body of the box, after which 110 the tray is replaced the contents thereof remaining undisturbed.

It will be evident that by using the improved tray, the retailer is assured of an attractive display of his goods at all times and the labor and expense of keeping the stock 5 in order will be lessened.

It will be evident that any shape of box may be used with the tray, the tray being shaped to fit the box.

I claim:

- 10 1. The combination with a box, of a tray seated therein, said tray having at one end an angular clip, provided at each end with an overlying flange, one of which is passed through the bottom of the tray and overlies the upper face thereof, and the other being adapted to engage the edge of the box, a flexible strand secured by one end to the under face of the bottom of the tray at approximately the center thereof, and having 20 at its free end a clip for engaging the edge of the box opposite the point of engagement of the first named clip, said strand being of a length sufficient to support the edge of the tray flush with the edge of the box.
- 25 2. The combination with a box, of a tray seated therein, and provided at one end with means for engaging the adjacent edge of the box, a flexible strand secured by one end to the under face of the bottom of the tray at approximately the center thereof, and having 30 at its free end a clip for engaging the edge of the box opposite the point of engagement of the first named clip, said strand being of a length sufficient to support the edge of the tray flush with the edge of the box.

3. The combination with a box, of a tray seated therein, and provided at one end with means for engaging the adjacent edge of the box, and a flexible strand secured by one 40 end to the under face of the tray at approximately the center thereof, and provided at the other end with means for engaging the opposite edge of the box, said strand being of a length sufficient to support the edge 45 of the tray flush with the edge of the box.

4. The combination with a box, of a tray seated therein, and provided at one end with means for engaging the adjacent edge of the box, and a flexible strand secured by one end 50 to the bottom of the tray and provided at the other end with means for engaging the opposite edge of the box, said strand being of a length sufficient to support the edge of the tray flush with the edge of the box and being attached at a point remote from that edge of the box engaged by the means at the ends of the strand for the purpose set forth.

5. The combination with the box of a tray seated therein, and provided at one end with 60 means for engaging the edge of the box, and at the other end with a flexible strand whose one end is connected with the box adjacent to its edge, and the other with the bottom of the tray at a point remote from said edge, 65 said strand being of a length sufficient to support the tray with the edge thereof flush with the edge of the box.
